REAR SIGHT FOR GUNS

Albert Sherman, Hampton, Va.

Application February 10, 1936, Serial No. 63,134

8 Claims. (Cl. 33—56)

My invention relates to a rear sight for a gun. The most satisfactory types of rear sights now employed are peep-sights with micrometer-click adjustments for windage and elevation. Such sights, however, because of the workmanship required to make them satisfactory at present are too expensive to be sold with the inexpensive class of gun. The rear sights generally fitted to such cheap guns are wholly unsatisfactory in the manner of their adjusting. The object of my invention is to provide a novel design for a rear sight which possesses the desirable features of micrometer-click adjustments without play for windage and elevation, and of sturdy construction, yet is so simple in structure as to enable it to be manufactured at very low cost, and thus provide the cheap gun with a highly satisfactory rear sight.

In the accompanying figures and specification, I will describe one embodiment of my invention. Figure 1 is a side view and Figure 2 is an end view of my invention. Referring to the figures, the body 3 of this gun sight is substantially a composition of springs, and is provided with a mounting portion 4. This mounting portion 4 comprises means for suitably fastening the sight to the breech of a gun as desired. Although any suitable means may be used, for purposes of illustration I have shown a number of holes 5 for fastening the sight by means of screws to the breech of a gun. The mounting portion 4 connects with the inner arm 6 of leaf spring 7. The outer arm 8 of leaf spring 7 is provided near its free end with some manner of boss 9 drilled and tapped to receive adjusting screw 10. In Figure 1, the outer arm 8 is shown partially cut away to show the inner arm 6 connecting with the mounting portion 4. The outer arm 8 attaches by means of the connecting portion 11 to the lower arm 12 of spring 13. The upper arm 14 of spring 13 is provided near its free end with a boss 15 similar in construction to boss 9 and adapted to threadably receive adjusting screw 16. Sighting member 17 suitably connects to the free end of spring arm 14 and is provided with a means for sighting such as peepholes 18. In my disclosure, for purposes of illustration I have shown two vertically disposed peepholes 18. In this illustration the adjusting screws 10 and 16 are provided with similarly constructed notched heads 19 and 20 respectively. Although any suitable type of notch may be used, for purposes of illustration, I have shown V-shaped notches. Leaf springs 21 and 22 extend from spring arms 6 and 12 respectively and are adapted to engage under initial springing in the notches of heads 19 and 20 respectively for

holding adjusting screws 10 and 16 respectively in their set positions. In this illustration I have also shown nuts 23 and 24 which may be used for further locking the adjusting screws 10 and 16 respectively in any desired positions, or which may be used to entirely supplant the leaf springs 21 and 22 if considered desirable. The leaf springs 21 and 22 may be provided with graduations 25 and 26 respectively. Pointers 27 and 28 may be attached to spring arms 8 and 14 respectively for the purpose of indicating the graduations 25 and 26 respectively. 5 10

The manner of operation of my invention is as follows: the adjusting screw 10 abuts against the surface of spring arm 6 and maintains the spring arms 6 and 8 apart against the action of spring 7. Thus it is evident that manual rotation of adjusting screw 10 provides movement of the sighting member 17 laterally (in Figure 2) with respect to mounting portion 4. On manually rotating adjusting screw 10, the leaf spring 21 is adapted to deflect and engage successive notches in the head 19 of adjusting screw 10 as the adjusting screw is rotated. The leaf spring 21 thus clicks when adjustment is being made and holds the adjusting screw 10 in any position to which it is set that corresponds with a notch in the head 19. Similarly, the adjusting screw 16 abuts against the surface of spring arm 12 and maintains the spring arms 12 and 14 apart against the action of spring 13. Thus it is evident that manual rotation of adjusting screw 16 provides movement of the sighting member 17 vertically with respect to mounting portion 4. The leaf spring 22 acts in a similar manner to leaf spring 21 to hold the adjusting screw 16 in any position to which it is set that corresponds with a notch in the head 20. Nuts 23 and 24 may be screwed manually against bosses 9 and 15 respectively to maintain locking of the adjusting screws 10 and 16 respectively in any positions desired. The transverse and vertical settings of the sight are indicated by the positions of the notched heads 19 and 20 respectively, and the positions of the pointers 27 and 28 respectively relative to the graduations 25 and 26 respectively. In the preceding description, the sighting member 17 was provided with two peepholes 18 disposed one vertically above the other. The lower peephole is for sighting at objects within a certain range and the upper peephole is for sighting at objects within a succeedingly greater range. This arrangement of peepholes reduces the movement apart of the spring arms 12 and 14 relative to each other which is required to obtain sighting over a 50 55

large range. It is evident that as many peepholes as may be considered desirable and of any desired character may be provided.

From the figures and description, it is obvious that the adjustment provided, the windage or the elevation is adapted to be very sensitive and accurate. It is also evident that the entire body, including the mounting portion 4, the springs 7 and 13, the bosses 9 and 15, the leaf springs 21 and 22, the pointers 27 and 28, and the sighting member 17 can be stamped and formed from a single piece of metal if so desired, without the slightest necessity for close fits for the total elimination of play, such as required for the usual types of sights; all of which being adaptable to very economical manufacture. While I have described but one embodiment of my invention, it will be obvious to anyone skilled in the art that it is not so limited but is susceptible to various changes and modifications without departing from the spirit thereof.

I claim:

1. In a sight of the class described, a sighting element, two U-springs, the outer end of one arm 25 of one of said springs being connected to the outer end of an arm of the other spring, each of said U-springs being disposed to allow movement of the aperture of the sight in one of two mutually perpendicular directions respectively, adjustable means for separating under stress the arms of said springs for providing said movement of the aperture of the sight, the free end of one spring being connected to the gun, the free end of the other spring carrying the sighting element. 30

35 2. A device of the class described comprising a supporting element for mounting the device on a gun, a sighting plate provided with a plurality of apertures, two U-springs attached together by one arm of each spring, the unattached arm 40 of one of said springs being connected to the supporting element, the unattached arm of the other U-spring being connected to and carrying the sighting plate, each U-spring being disposed to allow movement of the sighting plate in one of 45 two mutually perpendicular directions respectively.

3. A device as described in claim 2 and further characterized by having adjustable means for separating the arms of said U-springs under 50 stress for controlling the aforesaid movement of said sighting plate.

4. A sight of the class described characterized by having two U-springs, the outer end of one arm of one of said springs being connected to 55 the outer end of an arm of the other spring, and disposed to allow windage and distance adjustment of the sight, means for separating the arms of the respective windage and distance U-springs under stress for controlling the adjustments of 60 the sight, and a sighting element mounted upon

the free end of one arm of one of said U-springs.

5. In a device of the class described, a supporting element for mounting said device on a gun, a sighting plate having a plurality of apertures, means for connecting said sighting plate to said supporting element comprising two U-springs, an end of one spring being connected to an end of the other, each of said springs being adapted to allow motion of said sighting plate relative to said supporting element in one of two mutually perpendicular directions respectively, a threaded recess in one arm of each of said U-springs, adjusting screws adapted to thread into the respective recessed arms of the U-springs and to abut against the unrecessed arms for spreading the arms of said U-springs apart in an adjusting action. 10 15

6. In a device of the class described having a sighting element, two resilient elements, each of said resilient elements having two ends adapted to move in only one direction relative to each other, one of said resilient elements being connected at one end to and carrying said sighting element and being connected at its other end to an end of the other of said resilient elements, 20 25 each of said resilient elements being adapted to allow movement of said sighting element in one of two mutually perpendicular directions respectively.

7. In a device of the class described having a sighting element, two resilient elements, each of said resilient elements having two ends adapted to move in only one direction relative to each other, one of said resilient elements being connected at one end to and carrying said sighting element and being connected at its other end to an end of the other of said resilient elements, each of said resilient elements being adapted to deflect in one of two mutually perpendicular directions respectively, and means for independently adjusting 30 35 the deflections of said resilient elements. 40

8. In a device of the class described, a supporting element for mounting said device on a gun, a sighting plate having a plurality of apertures, means connecting said sighting plate to said supporting element comprising two U-springs connected in series, each of said springs being adapted to allow motion of said sighting plate relative to said supporting element in one of two mutually perpendicular directions respectively, a 45 threaded recess in one arm of each of said U-springs, adjusting screws adapted to thread into said recessed arms and to abut against the unrecessed arms for spreading the arms of said U-springs apart, said screws being provided with 50 notches, one arm of each of said U-springs being extended to form cantilever springs adapted to coact with the respective notched screws for holding 55 said screws in their set positions.
